Inventor:

Herman Garrison

UNITED STATES PATENT OFFICE.

HERMAN GARRISON, OF CHICAGO, ILLINOIS.

CAN OPENER.

Application filed April 30, 1928. Serial No. 273 816.

The object of this invention is, to effect a certain improvement in the commonest type of can opener, which is characterized by a terminal guiding fulcrum and a downwardly offset uppercut blade extending far enough past the stock to permit of penetration.

Commercial openers of this type have a cutting edge of about one inch in length, no practical way of inserting and operating a longer knife having been worked out. I employ a cutting edge of one and one-half inches.

An attempt to use a knife of this length develops a number of difficulties. Some of these are solved by previous applications on which patents have been granted, and solutions of others will be reserved for future applications.

Fig. 1 exhibits a side view of the opener, showing the stock A fitted into a handle, and knife, comprising blade B and shank C, the latter being riveted to the stock. Cutting edges are indicated by double lines, the lower being required for the introduction of the lengthened knife into the can.

Fig. 2 is a fragmentary top plan view, showing the end of the stock A bent aside to form the fulcrum member D. The blade is curved to fit a round can, and the widening of its vertical projection is due to a vertical curve in the blade.

Fig. 3 is a view of the anterior face of the fulcrum member, showing the notch E which forms the guiding fulcrum.

Fig. 4 represents in alternative constructions, α and β , a vertical section of the blade on the line 4—4 of Fig. 1, looking in the direction of the arrow.

Figs. 5, 6, 7, 8, and 9 will be used in explaining the operation of the instrument with relation to the vertical curvature exhibited in Fig. 4, which forms the basis of the claim which is sought by this application.

The difficulties encountered in operating the lengthened knife with which this application is concerned, and which are met by either construction of Fig. 4, are two in number, and will be considered in order.

When any opener of this type is to be inserted, the blade is thrust vertically downward until the end of the stock strikes the top of the can, as illustrated by a diagram, Fig. 5. Insertion is completed by composition of two motions, whose directions are indicated by the arrows. With the lengthened knife, the

principal of these motions is that indicated by the upper arrow, which is effected by prying the knife backward into the can. For this reason the back of the knife is sharpened.

A long initial gash will be made in the can, which may be almost the length of the knife, equivalent to half a dozen kerfs made by the short blades now in use.

Fig. 6 shows by a dotted line K F an incision of sufficient length to permit the can to be opened. The double line K H indicates the initial gash above referred to, which is made by the lower cutting edge.

Fig. 7 shows part of a can in axial section, and a vertical section of an uncurved blade in the process of descending into the can by means of its lower cutting edge, somewhere on the line K H. The displaced rim of tin at the edge of the severed portion of the top of the can is bent down to form the burr Z.

This burr is troublesome. After the knife has been inserted in the initial incision K H, and we attempt to move it forward, it is liable to stick fast in the incision. This is occasioned both by the burr, which will catch onto the upper cutting edge, and by the narrowness of the long incision, through which the shank can not be moved with sufficient ease and celerity.

To remove this obstacle to operation, I widen the incision K H, and this result is attained by making the blade concavo-convex in vertical section, as shown in Fig. 4. This vertical curving may embrace the whole width of the blade, as shown by α , or only a part of it, as in β .

The second difficulty to be considered in this application, and which is met by the same construction, is occasioned wholly by the burr Z. This will extend along the inner side of the curve K H, and has the effect of reinforcing the edge of the severed portion of the top of the can, so that it resists bending.

The incision K F completed, the operator raises the severed portion, expecting it to bend back on the line F K, but the stiffened edge K H remains in position and the tin bends on the line F H, thus losing the advantage of the initial incision K H.

Fig. 8 shows the vertically curved blade of α , Fig. 4, descending. It will make a clean cut on the side toward the center of the can, the displaced tin being pushed down by the convex side of the blade, in the position shown by Fig. 9.

This construction applied to the rearward part of the blade will prevent the formation of the burr on the inner edge of the incision adjacent the point K, so that the loosened part of the top of the can will bend back on the line F K.

I claim:

A can opener in the form of a lever of the second class, having a guiding fulcrum formed at the end of a handled stock, and a downwardly offset uppercut knife secured by

its shank to said stock, its blade extending forward past the guiding fulcrum; said knife having a cutting edge on its lower margin, and being laterally curved in the direction of its length; and the blade, in a region posterior to the fulcrum, being laterally curved in the direction of its vertical width, presenting in vertical section a curve which is concave on that side which faces the center of curvature 15 of the directional curve of the knife.

HERMAN GARRISON.
